US0D1001728S

(12) **United States Design Patent** (10) **Patent No.:** **US D1,001,728 S**
(45) **Date of Patent:** **** Oct. 17, 2023**

(54) **POWER TOOL BATTERY PACK**

(71) Applicant: **Shenzhen Binghuo Electronic Commerce Co., Ltd.**, Guangdong (CN)

(72) Inventor: **Dongxing Li**, Jiangxi (CN)

(**) Term: **15 Years**

(21) Appl. No.: **29/861,981**

(22) Filed: **Dec. 5, 2022**

(51) LOC (14) Cl. **13-02**

(52) U.S. Cl.

USPC **D13/103**

(58) **Field of Classification Search**

USPC D8/61, 68, 69; D13/103, 107, 108, 119, D13/120, 173; D14/253

(57) **CLAIM**

The ornamental design for a power tool battery pack, as shown and described.

DESCRIPTION

FIG. 1 is a perspective view of a power tool battery pack showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1; and,

FIG. 10 is an enlarged view of a portion indicated with numeric 10 in FIG. 1.

The dash-dash broken line represents portions of the power tool battery pack that form no part of the claimed design. The dash-dot broken line FIGS. 1, 9 and 10 depict the boundaries of the enlargements that form no part of the claimed design.
